(57) **CLAIM**

The ornamental design for a log splitter, as shown and described.

DESCRIPTION

FIG. 1 is a front perspective view of a log splitter in an inverted position with the support legs collapsed, showing our new design;

FIG. 2 is a rear elevation view thereof with an inserted lever;

FIG. 3 is a front elevation view thereof;

FIG. 4 is a bottom plan view thereof;

FIG. 5 is a top plan view thereof;

FIG. 6 is a right side view thereof;

FIG. 7 is a left side view thereof; and,

FIG. 8 is a front elevation view of the log splitter in reduced size, with the support legs collapsed, the lever removed, and operated by a tractor.

The broken lines of a log in FIGS. 1 and 8, and of a tractor in FIG. 8 depict environment that form no part of the claimed design.
